VARIABLE CONDENSER

Filed Dec. 16, 1924

Inventor:
George H. Robbs
by D. Hammer
Atty.

UNITED STATES PATENT OFFICE.

GEORGE H. NOBBS, OF WATERTOWN, MASSACHUSETTS.

VARIABLE CONDENSER.

Application filed December 16, 1924. Serial No. 756,222.

To all whom it may concern:

Be it known that I, GEORGE H. NOBBS, a citizen of the United States, and resident of Watertown, in the county of Middlesex and State of Massachusetts, have invented an Improvement in Variable Condensers, of which the following is a specification.

This invention relates to that class of electrical variable capacity condensers of the plate type, which are widely used in radio receiving sets and which generally comprise two sets or groups of parallel, semi-circular plates, one group, called the stator, being stationary, and the other, called the rotor, being mounted for rotation to permit interposition of its plates with the stationary plates to a varying extent, thereby to vary the capacity of the apparatus.

It is well known that, to secure satisfactory results in a radio receiving set, a balance, which is as nearly perfect as possible, must be secured between the inductance and capacity of the receiving circuits. Variation of the inductance is usually secured by means of the taps which are placed in contact with one or more turns of wire on the inductance coil, but the variation secured by cutting in or out of even a single turn of the coil is so great that accurate adjustment of the inductance to the capacity of the circuit in this manner is ordinarily impossible. The adjustment of the capacity to the inductance is usually secured by means of a condenser of the type above referred to, but even where the inductance has been adjusted to established conditions as closely as possible by means of the taps, yet inductance is likely to vary to such an extent under different conditions, that it is usually difficult to determine, without making numerous tests, what range of capacity will be necessary to secure the desired balance.

Condensers of the type referred to are now made to secure widely varying ranges of capacity between a minimum, which is usually nearly the same, and the maximum which is required, this variation being usually secured by varying the number, size and proximity of the plates. At present dealers carry condensers in five or more different sizes, designed to give a corresponding number of stages of maximum capacity. In many instances it is necessary to make tests with several condensers having different maximum capacities, before it is ascertained what particular condenser will give

the most satisfactory result under the conditions at hand.

The principal reason for the necessity or desirability of using condensers having different degrees of maximum capacity for different conditions is as follows:—The whole range of capacity of any given condenser of the above type is secured by turning the rotor through 180°. If a condenser of sufficient maximum capacity for all conditions is employed, the result will be that the correct tuning positions of the rotor for certain stations which are broadcasting within certain relatively low limits of wave length, requiring capacities much less than the maximum, will be crowded into a relatively small portion of its total range of adjustment, so that the extent of adjustment of the rotor necessary to tune to these stations of relatively low wave length will be so slight that the different adjustments will practically coincide, thereby making it impossible to tune out one station in favor of another. On the other hand, if the range of capacity of the condenser is so reduced that the rotor must be adjusted throughout its entire range of movement to adjust the capacity to all of these stations of relatively low wave length, the extent of adjustment from one position to another to secure the correct tuning therefor will be greatly increased, thereby correspondingly increasing the selectivity of the receiving set for these stations, and making it possible to tune in stations which could not be tuned in if the maximum capacity of the condenser was substantially greater.

It has been attempted to obviate the necessity of making tests with condensers of different maximum capacity to secure desired results by providing a condenser having several groups of plates, one or more of which may or may not be employed according to conditions, and, while such an apparatus, to some extent, obviates the difficulty, yet the step up from one maximum capacity to the next is so great with such an arrangement that it is still impossible to adjust the rotor so as to secure the desired degree of selectivity as to certain stations requiring intermediate degrees of capacity.

The objects of my invention are to provide a condenser of the type above referred to, having means whereby its maximum capacity may be readily increased by small steps or stages from a fixed minimum ca-

6 pacity to any maximum capacity which is likely to be required, the number of stages of increase in maximum capacity of the condenser to be in direct proportion to its greatest possible range of capacity, so that 10 a correspondingly large number of ranges of capacity from the minimum may be secured by a semirotation of the rotor, whereby the particular limit of maximum capacity which may be desired under any particular conditions may be readily secured by means of a single apparatus. Also, to provide a condenser having the above specified characteristics which shall occupy 15 but slightly greater space, and be but slightly more expensive to construct than the ordinary condenser of the greatest maximum capacity.

I accomplish these objects by providing 20 a condenser of the type above identified with means whereby any one or more of the stator plates may be readily placed in or removed from the condenser circuit, independently, as circumstances may require. 25 For a more complete understanding of my invention, reference is made to the accompanying drawing, forming a part of this specification, in which:

Fig. 1 is a plan view of an electrical condenser embodying a preferred form of my invention.

Fig. 2 is a sectional view at line 2—2 of Fig. 1.

Fig. 3 is an end view thereof.

Fig. 4 is sectional view at line 4—4 of Fig. 1 on an enlarged scale.

Fig. 5 is a sectional view, at line 5—5 of Fig. 1 on an enlarged scale.

Fig. 6 is a detail view of portion of one of the stator plates and its connecting device.

As shown in the drawing, I provide a main frame which consists of a pair of end plates 10 and 12, of electrical insulating material, which are connected by a series of bolts 14 having clamping nuts 15 and 16 at each end, the nuts 15 being adapted to be connected to the instrument panel in the usual manner. The usual semi-circular, spaced rotor plates 18 are mounted on, and electrically connected to a shaft 20, which is rotatably mounted in the end plates 10 and 12 and, in practice, will be provided with a handle in front of the panel for convenient manipulation. A spring contact 22 is provided for the rear end of the shaft 20, to which one terminal 23, of the circuit, is connected. The stator plates 24, which are similar in shape, thickness and spacing to the rotor plates, are mounted in parallelism thereto on the bolts 14, said plates 24 being electrically insulated from said bolts by glass bushings 25 and from each other by interposed, insulating, spacing washers 26, washers or bushings 27 of somewhat greater thickness or length than the washers

26, being provided between the rear stator plate and the rear end plate 10, and the end plates, stator plates and washers being all clamped firmly together by means of the nuts or bolts 14. The arrangement of the 70 stator plates is such that when the rotor plates are rotated they will be interposed between the stator plates without actually coming in contact therewith, as is usual in this class of devices. It is to be understood in this connection that the number of stator and rotor plates shown is merely illustrative and that, in practice, the number employed will be sufficient to give the maximum capacity likely to be required under all conditions of use.

A metal rod 28 is mounted in the back plates 10 and 12 adjacent one of the tie rods 14, and is held in position by nuts 29 threaded thereon and clamped against said plates. The rear end portion of said rod is preferably used as a binding post and has a thumb nut 30 thereon for connecting the other circuit terminal 31 thereto. A series of switch levers 32 are pivotally mounted on said rod 28 in electrical contact therewith and with each other, said levers being spaced apart by non-insulating washers 34 and held in close contact with each other by a coiled spring 35, the arrangement being such that each lever is so held that it swings in the plane of a corresponding stator plate 24. Each lever 32 is provided with a contact face 33 at one end, which is made slightly eccentric to the axis 30 about which it swings, and is so arranged that it may be swung into wedging engagement with the corresponding stator plate in the plane of which it swings. For the purpose of increasing the arc, or area of contact between the levers and plates, each plate 24 is preferably provided with a recess 36, see Fig. 6, into which the contact face of the corresponding lever swings, the shape of the recess being such that, when the lever is pushed into as firm engagement as possible with the plate, the lever and plate will be engaged throughout practically the entire bottom surface of the recess. A stop rod 38 may be provided to limit the 115 opening, swinging movement of the levers.

In adjusting the device to any particular set of conditions, it will first be decided approximately how many stator plates will be required to secure the maximum capacity necessary for such conditions, and then a corresponding number of the switch levers 32 will be swung into operative relation with the corresponding plates, so that electrical connection will be established between such plates and the terminal attached to the rod 28. The rotor will then be moved from the minimum capacity position of Fig. 2 to secure, if possible, the correct balance with the inductance in the usual manner. If the maxi-

mum capacity is found to be too high then one or more of the levers will be restored to its vertical position, or, if it is found to be too low, then one or more additional plates 5 will be placed in the circuit by moving the corresponding switch levers 32 to their engaging positions, as will be obvious. As all the stator plates are insulated from each other, and are only electrically connected to 10 each other and to the terminal 31 through their corresponding switch levers 32, it follows that the plates not connected will, for the time being at least, be merely dead metal, but as it has been conclusively proven that 15 the presence of the dead plates does not appreciably effect the efficiency of the receiving set, this fact is not objectionable. The variation in maximum capacity secured by cutting in or cutting out a single plate is 20 so small that a very accurate adjustment of the maximum capacity desired may be secured, so that any one of a large series of ranges of capacity from the minimum may be brought in by a semi-revolution of the 25 rotor in a single condenser constructed as above described.

It will be apparent that, under all ordinary conditions of use, a substantial number of stator plates will always be employed, 30 so that, under such conditions the connection between such plates and their terminal might be of a more permanent form than through the switch levers. However, so far as my invention is concerned it will be apparent that 35 it is immaterial whether the disconnectable plates are used in connection with permanently connected plates or not.

While I have shown the most satisfactory means of which I am at present aware for 40 cutting the stator plates in and out of action, yet it will be understood that other satisfactory means for the purpose may be employed which are within the scope of my invention.

45 I claim:

1. An electrical condenser comprising a group of stator plates and a group of rotor plates arranged to be moved between said stator plates to vary the capacity, a terminal for each group of plates, the terminal for the rotor plates being electrically connected thereto, means for supporting said stator plates out of electrical contact with each other and the terminal thereof and a 50 series of switches corresponding in number to the stator plates and movable independently of each other to establish electrical connection between the respective stator plates and their terminal.

60 2. An electrical condenser comprising a group of stator plates and a group of rotor plates arranged to be moved between said

stator plates to vary the capacity, a terminal for each group of plates, the terminal for the rotor plates being electrically connected 65 thereto, means for supporting said stator plates out of electrical contact with each other and the terminal thereof and a series of switch levers electrically connected to the stator terminal and arranged to be swung 70 separately from an inactive position into engagement with a corresponding stator plate to establish an electrical connection with its terminal.

3. An electrical condenser comprising a 75 series of stator plates and a series of rotor plates arranged in parallelism therewith for variable interposition with the stator plates to vary the capacity, means for supporting said stator plates out of electrical contact 80 with each other, a series of switch levers, each mounted to swing in the plane of one of said stator plates and having a contact face arranged to be engaged with the edge thereof to make electrical connection therewith when the lever is swung from a disengaged to an engaging position and a pair of electrical terminals one being connected to the rotor plates and the other to said 85 switch levers. 90

4. An electrical condenser comprising a series of stator plates and a series of rotor plates arranged in parallelism therewith for variable interposition with the stator plates to vary the capacity, means for supporting 95 said stator plates out of electrical contact with each other, a pivot rod having a series of switch levers each mounted on said rod in electrical contact therewith to swing in the plane of one of said stator plates and having 100 a contact face arranged to be engaged with the edge of its corresponding stator plate to make electrical contact therewith and a pair of terminals one electrically connected to said rotor plates and the other to said 105 pivot rod.

5. An electrical condenser comprising a series of stator plates and a series of rotor plates arranged in parallelism therewith for variable interposition with the stator plates 110 to vary the capacity, means for supporting said stator plates out of electrical contact with each other, a series of switch levers, each mounted to swing in the plane of one of said stator plates and having a cam 115 face arranged to be swung into wedging engagement with the edge of its corresponding stator plate to make electrical contact therewith, and a pair of terminals electrically connected respectively, one to said rotor 120 plates and one to said switch levers.

In testimony whereof, I have signed my name to this specification.

GEORGE H. NOBBS.
